UNITED STATES PATENT OFFICE.

JOHN H. HURT, OF CHERRYVILLE, NORTH CAROLINA, ASSIGNOR OF ONE-HALF TO DAVID P. RHODES, OF CHERRYVILLE, NORTH CAROLINA.

LOOM.

SPECIFICATION forming part of Letters Patent No. 690,367, dated December 31, 1901.

Application filed April 20, 1901. Serial No. 56,744. (No model.)

To all whom it may concern:

Be it known that I, JOHN H. HURT, of Cherryville, in the county of Gaston and State of North Carolina, have invented certain new and useful Improvements in Looms, of which the following is a specification.

This invention relates to looms, and particularly to the let-off mechanism thereof, and is designed also with reference to the take-up mechanism as well.

The invention relates not alone to any specific type of loom, but is capable of being employed with advantage in connection with any loom of any kind employing a positive let-off.

The object of my invention is to provide means for preventing a loom from letting off the warp and making thin places in the cloth such as results when the warp-threads are moved any distance after the cessation of the throwing-in of the filling or weft for either a short or a long pick; and a further object of my invention is to provide means additional to those which stop the let-off for also stopping the take-up.

To these ends my invention consists in the construction and combination of parts substantially as hereinafter described and claimed.

In the accompanying drawings, Figure 1 represents an end elevation of a well-known form of loom having applied thereto an embodiment of my invention, a portion of the frame being broken out to show the take-up gearing supposed to be located at the farther end of the loom. Fig. 2 represents a detail section on line 2-2 of Fig. 1. Fig. 3 represents a detail front-elevation of a portion of the frame and some of the parts supported thereby, including the belt-shipper. Fig. 4 is an enlarged perspective view of the means for preventing the operation of the let-off mechanism. Fig. 5 is a similar view representing a modification hereinafter referred to.

The frame of the loom is represented at 10, the part of the frame at the farther end, looking at Fig. 1, being indicated at 10^a. The gear on the warp-beam is represented at 11, and 12 is the whip-roll, 13 one arm of the lay, 14 the breast-beam, 15 the gear or pinion on the cloth or take-up roll, 16 the take-up

ratchet-wheel, 17 the pawl, which is reciprocated by any suitable means to impart a step-by-step rotation to the ratchet-wheel 16, all of these being represented as parts of a well-known form of loom. The pinion 18, meshing with the gear 11, the worm-wheel 19, secured to rotate with the pinion 18 and meshing with a worm 20 on a vertical shaft 21, which is mounted in bearings in a stand or bracket attached to the frame 10, said shaft 21, having a ratchet 22, operated by a pawl 23 at one end of a lever 24, pivoted loosely on the worm-shaft 21, the rod 25, connected with the other end of the lever 24, said rod 25 having its other end connected with a lever 26, are also all of a well-known construction, said lever 26 being connected to the whip-roll support through the rod and spring connection, such as shown in the drawings, all 70 being well known and needing no description herein. The lever 24 is actuated so as to cause the pawl to actuate the ratchet 22 and effect the positive let-off by means of the worm-gearing, said lever being moved in the 75 proper direction by the rod 25, said rod 25 being drawn in the proper direction by means of the rod 28, pivoted to the arm 13, and having an eye surrounding the rod 25, a stop-block 27 on the rod 25 being employed, as 80 usual, to cause the rod 28 to exert the necessary pull on the rod 25. All of this mechanism is also well known.

So far as my invention is concerned, the mechanism for oscillating the pawl 23 about 85 the axis of the shaft 21 may be variously modified without departing from the principle of my said invention, and the style of loom may be widely varied.

I will now proceed to describe one way in 90 which I have carried my invention into practice.

Referring to Figs. 1, 2, and 4, a short lever 30 is shown as mounted to oscillate upon the worm-shaft 21, said lever carrying at its outer 95 end a curved shield 31, extending over the teeth of the ratchet 22 and adapted to be swung to a position where the oscillations of the pawl-lever 24 will cause the point of the pawl to slip back and forth over said shield 100 without engaging the teeth of the ratchet. Normally this shield 31 remains in a position

such as indicated in Figs. 2 and 4; but when the weft-detector commonly employed in looms, or any other means are employed designed to automatically stop the loom upon the exhaustion or breaking of the weft operates, the shield 31 is moved to a position, so as to be interposed between the pawl and the ratchet. I will now describe one way in which to effect the motion of the shield. The 10 end of the lever 30 opposite the shield 31 is provided with a pin 32, to which is connected one end of a rod 33, the opposite end of said rod being connected to a lever 34, pivoted at 35, to a suitable part of the frame. The upper 15 end of said lever 34 is connected by a link 36 with an arm 37 of a rock-shaft 38, mounted in suitable bearings below the breast-beam and extending across the loom. The other end of the rock-shaft 38 (see Fig. 3) 20 is provided with an elbow-arm 39, which is adapted to engage the belt-shipper lever 40 and throw it out of the notch of the retaining-plate 41, so that said lever 40 will be swung on its pivot by means of the spring 42 25 and shift the belt from the fast to the loose pulley, and thus stop the loom.

I have not attempted to illustrate any special form of weft-detector, since I may employ any well-known or preferred type. It 30 is sufficient to enable any one to understand the principle of my invention to state that the weft-detector will be such that immediately upon the failure of the filling the shaft 38 will be rocked by the mechanism controlled 35 by said weft-detector, such rocking movement of the shaft 38 being in a direction to force the upper end of the belt-shipper lever 40 out of the notch of the retaining-plate 41, resulting in the shifting of the belt to the 40 loose pulley, as described. This movement of the shaft 38 is in a direction to cause the arm 37 to move in the direction of the arrow in Fig. 1, causing the rod 33 to move in the direction of the arrow adjacent thereto, 45 and thus carry the shield 31 under the point of the pawl 23, as will now be obvious. Therefore, although the inertia of the parts of the loom may cause one or more picks to be made after the belt has been shifted there will be 50 no let off of the warp, owing to the fact that the shield is interposed, as stated, at the instant of the movement of the shaft 38. I prefer to make connections also with the take-up mechanism, so as to prevent the operation 55 thereof simultaneously with the stoppage of the operation of the let-off pawl. One way in which I may carry this part of my invention into effect is by means of a catch-arm 43, secured to the shaft 38 and having a cam-shaped lower end which engages beneath a finger 44, carried by the arm of the take-up pawl 17. The hook or cam-shaped end of the arm 43 is so formed that when the shaft 38 is rocked, as has been mentioned, the pawl 17 60 will be lifted sufficiently to clear the teeth of the ratchet-wheel 16, and thus instantly stop the take-up.

Referring to Figs. 4 and 5, it will be seen that there is a slight difference in the pawl and the shield. The form of shield shown in Fig. 4 is intended to be adapted for use on looms which are already constructed with a let-off pawl such as shown in said figure. By forming the pawl with a toe rising above the plane of the ratchet 22, such as indicated in Fig. 5 at 23^a, a shield may be used such as indicated at 31^a in said Fig. 5, said shield thus oscillating in a plane above the plane of the upper edge of the ratchet 22. In some forms of looms I prefer to employ such a pawl and shield as just described in connection with Fig. 5.

Having now described and illustrated sufficiently one form or embodiment of my invention, I wish it to be distinctly understood that I do not limit myself to the details of construction shown in the drawings, for it is obvious that my improvements may be variously modified by any skilled loom mechanic, so as to apply it to other forms of loom than that which I have somewhat conventionally illustrated.

I claim—

1. A loom comprising in its construction a positive let-off mechanism including a pawl and ratchet, a shield adapted to prevent engagement of the pawl with the ratchet, and connections between said shield and the power-controlling mechanism of the loom for operating the shield simultaneously with the first movement of the said power-controlling mechanism.

2. A loom comprising in its construction a positive let-off mechanism including a pawl and ratchet, a shield adapted to prevent engagement of the pawl with the ratchet, a belt-shipper, and means whereby movement of the belt-shipper to stop the loom will simultaneously operate the shield to prevent actuation of the let-off ratchet by the pawl.

3. A loom comprising in its construction a take-up and a positive let-off mechanism including a pawl and ratchet, a shield adapted to prevent engagement of the pawl with the ratchet, a belt-shipper, and means whereby the first movement of the belt-shipper to stop the loom will stop movement of the take-up mechanism and simultaneously operate the shield to prevent actuation of the let-off ratchet by the pawl.

4. A loom comprising in its construction a positive let-off mechanism including a pawl and ratchet, a shield adapted to prevent engagement of the pawl with the ratchet, a take-up mechanism including a pawl and ratchet, and connections between the said shield and the take-up pawl and the power-controlling mechanism of the loom whereby movement of the latter will simultaneously disengage the take-up pawl from its ratchet and move the shield to disengage the let-off pawl from its ratchet.

5. A loom comprising in its construction a positive let-off mechanism including a pawl

and ratchet; a lever mounted to oscillate on the axis of the ratchet and having a shield adapted to push the pawl away from said ratchet, a lever 34 mounted on the frame of the loom, a rod connecting said lever with the shield-lever, a rock-shaft 38 having an arm connected with the lever 34 and having a catch-arm 43, a take-up mechanism including a ratchet and pawl, said pawl having a finger 10 adapted to be operated upon by the catch-arm for elevating the pawl, and means for oscillating the shaft 38.

6. A loom comprising in its construction a positive let-off mechanism including a pawl and ratchet, a lever mounted to oscillate on the axis of the ratchet and having a shield adapted to push the pawl away from said ratchet, a lever 34 mounted on the frame of the loom, a rod connecting said lever with the

shield-lever, a rock-shaft 38 having an arm 20 connected with the lever 34 and having a catch-arm 43, a take-up mechanism including a ratchet and pawl, said pawl having a finger adapted to be operated upon by the catch-arm for elevating the pawl, a belt-shipper lever 25 having a spring for throwing it in one direction and a retaining-plate for holding it at one extreme of position in opposition to the said spring, and an arm carried by the shaft 38 and extending past the belt-shipper lever 30 and adapted to disengage said lever from the retaining-plate.

In testimony whereof I have affixed my signature in presence of two witnesses.

JOHN H. HURT.
